UNITED STATES PATENT OFFICE.

JOHN GLOVER GUNN, OF DOVER, GEORGIA.

TRACK GAUGE.

Application filed April 10, 1924. Serial No. 705,643.

My invention relates to improvements in track gauges of the kind which are adapted to run along a railway track and which serve to indicate the condition of the track as regards the distance between the rails.

The object of my invention is to provide a device of this kind which is simple in construction and efficient in operation and which will serve to automatically indicate any variations in the width of the track. A further object of the invention is to provide a device associated with the track gauge which is adapted to mark one of the rails whenever the gauge of the track exceeds or is less than a predetermined width. Other objects and advantages of the invention will be apparent from the following specification taken in connection with the accompanying drawings illustrating the same.

Referring to the drawings:

Fig. 1 is a plan view of my device, showing the same attached to a car, certain parts being broken away;

Fig. 2 is a side elevation of the construction illustrated in Figure 1;

Fig. 3 is an enlarged horizontal sectional view of one end of the device, this view being taken substantially on the plane of the rod or axle on which the wheels of the gauge are mounted;

Fig. 4 is a sectional view on the line 4—4 of Figure 3;

Fig. 5 is a sectional view on the line 5—5 of Figure 3;

Fig. 6 is a rear elevational view showing particularly the rail marking device;

Fig. 7 is a diagrammatic view illustrating certain electrical connections for operating a plurality of indicating lamps.

Referring to the drawings in detail, my device comprises a rod or axle 10 upon each end of which a flanged wheel 11 is rotatably mounted. The rod or axle 10 is connected to the car A by means of bars B, these bars at one end being securely clamped to the rod 10 and at their other ends they are pivotally connected to a projection C on the car. Such connection permits relative movement between the car and the gauge and enables the gauge to be lifted from the

track when desired and supported free of the same.

Each of the wheels 11 is mounted on the rod 10 in substantially the same way and the flanges thereof are forced outwardly against the rails 12 of the track. Each wheel 11 is rotatably mounted on a sleeve 13 preferably by means of roller bearings 14, these bearings being held in place by means of nuts 15 on the ends of the sleeves 13. Each of the sleeves 13 is mounted on the rod or axle 10 so as to have a limited slide motion longitudinally of this rod. This limited movement is provided by forming each sleeve 13 with diametrically opposite slots 16 and a pin 17 secured in each end of the rod or axle 10 engage at its opposite ends in these slots. It will thus be seen that these pins prevent rotation of the sleeves 13 but at the same time permit limited movement of the same longitudinally of the rod 10. The sleeves 13 are yieldingly forced outwardly, that is, toward the ends of the axle 10 by means of coiled springs 18 surrounding the rod 10. Each of these springs at its outer end bears against one of the sleeves 13 and at its inner end bears against a stop 19 rigidly pinned or otherwise secured to the rod 10.

To each of the sleeves 13 there is rigidly attached a bar or slat 20 and each of these bars or slats extends from its point of attachment to the sleeve 13 parallel with the rod 10 and to a point adjacent the sleeve on the opposite end of this rod. These bars or slats 20 are preferably secured to the sleeves 13 by means of straps 21 each of which extends around a sleeve and is bolted to its respective bar or slat 20. Each of the slats or bars 20 near the point where it is attached to the sleeve is provided with a keeper 22 which is adapted to slidably receive the free end of the bar or slat attached to the sleeve on the opposite side of the device.

From the foregoing it will be seen that the flanges of the wheels 11 will be pressed against the rails 12 by means of the springs 18. In case a portion of track is encountered in which the rails are farther apart or closer together than normal, it is apparent

that the wheels 11 will be caused to move away from or towards each other. This will result in relative movement between the bars or slats 20.

5 In order to indicate this relative movement between the bars or slats 20, an indicating arm 23 is pivotally connected intermediate its ends to one of these bars. One end of this arm is provided with a slot 10 which engages a pin 24 on the other bar so that relative movement between the bars 20 will cause movement of the member 23 about its pivot. To indicate this relative movement I provide an indicating scale 25 secured to one of the bars 20 and over which the indicating member 23 is adapted to move. This scale may be graduated in any manner desired.

Preferably the arm 23 is so formed as to 20 provide an electrical contact arm and the same is connected to one end of an electric circuit indicated at 26. The indicating scale or plate 25 is also preferably provided with a plurality of insulated electrical contact 25 points 27 and beneath this scale I provide a manually operable contact arm 28 which is connected to the other terminal of the electric circuit 26. It will be understood that the arm 28 is insulated from the frame and 30 also from arm 23 and may be placed in contact with any desired one of the contact elements 27 with the result that when the contact arm 23 moves into engagement with the particular contact 27 on which the arm 28 has been placed, the circuit is closed 35 through the electric circuit 26 and by this means a suitable signal such as a bell 29 mounted on the car A or at any other suitable point may be operated.

40 It may sometimes be desirable to have several signals arranged to be operated by the movements of the contact arm 23. Such an arrangement is shown particularly in Figure 7. The plate 25 is provided with a 45 plurality of contacts 25^a over which the arm 23 is adapted to pass. Each of these contacts forms a terminal of a separate electric circuit 26^a the other terminal of each of these circuits being connected to the arm 23. In 50 each of the circuits 26^a there is placed an indicating device, preferably a lamp 29^a, and these lamps are preferably of different colors. For example, the lamp which would be lighted when the arm 23 is in an extreme 55 position one way or the other way be red, the intermediate ones blue and the central one white. An arrangement of the kind just described may be conveniently placed on a passenger car in which inspectors are riding, and the color of the lights will show at 60 once the condition of the track as to gauge.

It is also desirable to have some kind of mark placed upon one or both of the rails of the track at the points where the gauge or 65 distance between the rails is not correct. I

have provided mechanism for doing this. Such mechanism comprises a lever 30 pivotally connected to one of the bars 20, preferably to one of the straps 21, this lever extending rearwardly and downwardly and 70 having two arms 30^a and 30^b arranged on opposite sides of the rail 12 and each provided with a marker of any suitable kind, one or the other of which is moved into contact with the rail 12 as the lever 30 is moved 75 about its pivot. To effect such pivotal movement of the lever 30, I pivotally secure thereto a link 31, this link also being connected to the other bar 20. It will thus be seen that when relative movement takes 80 place between the bars 20 such movement will result in causing one or the other of the arms 30^a, 30^b to move toward the rail and thus bring one of the marking devices against the rail. Such marks will serve at 85 once to show workmen where the gauge of the track is incorrect.

Having thus described the invention what is claimed as new and desired to be secured by Letters Patent is:

90 1. A gauge for indicating variations in the distance between the rails of a track comprising, in combination, a rod, a sleeve slidably and non-rotatably mounted on each end of said rod, a flanged wheel rotatably mounted on and movable with each of said sleeves, yieldable means for forcing said sleeves away from each other and the flanges of said wheels against the rails of the track, a bar connected to each of said sleeves and 95 movable therewith, and indicating means operable by the relative movement between said bars for indicating variation in the distance between said wheels.

100 2. A gauge for indicating variations in the distance between the rails of a track comprising, in combination, a rod, a sleeve slidably and non-rotatably mounted on each end of said rod, a flanged wheel rotatably mounted on and movable with each of said sleeves, yieldable means for forcing said sleeves away from each other and the flanges of said wheels against the rails of the track, a bar connected to each of said sleeves and 105 movable therewith, said bars being arranged side by side, a pointer pivotally connected intermediate its ends to one of said bars, means on the other bar for engaging one end of said pointer and an indicating scale carried by the bar on which the pointer is carried and arranged adjacent the other end of said pointer.

110 3. A gauge for indicating variations in the distance between the rails of a track comprising, in combination, a rod, a sleeve slidably and non-rotatably mounted on each end of said rod, a flanged wheel rotatably mounted on and movable with each of said sleeves, yieldable means for forcing said sleeves away from each other on said rod 115 120 125 130

and the flanges of said wheels against the rails, a bar connected at one end to each of said sleeves and movable therewith, said bars being arranged side by side, a keeper secured to the other end of each of said bars and engaging the other bar, a pointer pivotally connected intermediate its ends to one

of said bars, means on the other bar for engaging one end of said pointer, whereby movement is transmitted to said pointer by ¹⁰ the relative movement between said bars.

In testimony whereof I hereunto affix my signature.

JOHN GLOVER GUNN.
